PLATE FINISHING MACHINE

James F. Wilson, West Philadelphia, Pa., assignor
to Wood Newspaper Machinery Corporation,
Plainfield, N. J., a corporation of Virginia

Application December 17, 1938, Serial No. 246,317

7 Claims. (Cl. 29—21)

This invention relates to the type of machine wherein printing plates, particularly stereotype plates, are shaved to the proper thickness, cooled and delivered, ready for placing on the printing press.

The principal objects of the invention are to provide means whereby, as the plate enters the shaving arch a blast of air is directed against the printing surface of the plate to remove any chips or foreign matter which may injure the printing surface thereof, when it is clamped in the shaving arch; to provide means whereby water may be directed on either or both sides of the plate after it is delivered into the cooling stand, and to provide means whereby the plate passes over suitably arranged air pipes for blowing water off the inside of the plate before it is sent to the printing press.

Other objects and advantages of the invention will appear hereinafter.

Reference is to be had to the accompanying drawings, in which

Fig. 1 is a side elevation of a plate finishing machine showing a preferred form of this invention;

Fig. 2 is an end view showing the chip blowing mechanism;

Fig. 3 is a sectional view on the line 3—3 of Fig. 2;

Fig. 4 is an end view of the water blower mechanism;

Fig. 5 is a longitudinal sectional view of the same;

Fig. 6 is a side elevation partly in section of a modified means for controlling the air blast, and

Fig. 7 is an end view of mechanism in Fig. 6 as indicated by the arrow 7.

Referring to Fig. 1, plate P is placed on a platform 1 for inspection. After inspection it is passed on to rollers 2 which carry the plate through the finishing machine in a well known manner, preferably along a downwardly slanting series of rollers.

In traversing the machine, the plate is intercepted by a stop 3 which times the entering of said plate into a shaving arch 4 at the bottom of which it is halted by a stop 5. Said stop locates the plate within the arch 4 for suitable machining operations. After said machining, the stop 5 allows the plate to move along into a stand 6, where a water spray is directed against either or both plate surfaces. A stop 7 locates the plate in the stand 6.

All of the stops mentioned above are cam op-

erated by cams in a well known manner, not shown, said cams being secured to a knife shaft 8. The shaft 8 has secured thereto a knife blade 9 that finishes the inner surface of the plate, and it is necessary that all operating parts be synchronized with said blade.

The knife shaft 8 is revolved by a motor 10 which, through a pinion 11 and chain 12, drives a gear 13 secured to the knife shaft. In this way the knife shaft and all mechanisms attached thereto are put in operation.

When the arch 4 is clear and the knife blade 9 is in the proper position, the mechanism controlling the stop 3 will cause said stop to depress and allow the plate P to proceed into the arch 4. At this time a suitable cam 14 secured to the knife shaft 8 has its high part brought against a plunger 15 of a valve 16 causing said valve to be put in operation and releasing air.

The air is supplied from an outside source through intake piping 17, through piping 18 into a manifold 19, best shown in Fig. 2. The blast of air is projected outwardly from the arch against the outside surface of the plate before it enters the arch.

The manifold 19 is placed at the entering end of the arch 4 and contains holes suitably arranged to direct jets of air against the entire outer surface of the plate to remove any loose particles thereon which might be crushed into the plate in subsequent operations, thereby injuring the printing face.

It is evident from the above description that the air valve 16 will operate on every shaft revolution to impinge air or a similar fluid against the face of the printing plate as it enters the shaving arch.

The plate will, in the cycle of operation, eventually enter the stand 6 where water sprayed through suitable jets causes the plate to be cooled. Upon leaving said stand an accumulation of water remains on the plate, and that part remaining on the inner or concave surface of the plate would prove injurious to the press unless removed.

The plate upon leaving the stand 6 assumes a position P1 at the delivery end of the machine. Secured to this end of the machine is a manifold 20, having secured therein air spray pipes 21 and 22 placed parallel to the plate and in such position that holes drilled in said pipes will direct air against the concave surface of the plate.

Air inlet piping 17a is attached to a valve 23 whose plunger 24 is controlled by a cam 25 se-

cured to the knife shaft 8. The high point on the cam 25 will cause the valve plunger 24 to be depressed and allow air to pass through the valve 23 and piping 26 into the manifold 20 to be forced through the air spray pipes 21 and 22.

It is evident from the above description that the valve 23 will be operated on each revolution of the knife bar 8.

Since occasions arise when there is no plate at the position P1 during machine operation, the air exhaust through pipes 21 and 22 may not be desired. In this case an arrangement substantially as shown in Figs. 6 and 7 may be used. In this instance the plate, on moving along from the stand 6, is engaged by a suitably driven friction roller 29 that forces the plate along the machine until intercepted by a plunger 27 in a valve 28.

The force supplied by the roller 29 and the weight of the plate will be sufficient to cause the valve to be opened and release the air as previously described.

As shown in Fig. 6 the roller 29 is chain driven, from a sprocket 30, that in turn is operated by bevel gears 31 and 32, the latter of which may be carried on the knife shaft 8 and derive its motion therefrom.

Having thus described my invention and the advantages thereof, I do not wish to be limited to the details herein disclosed, otherwise than as set forth in the claims, but what I claim is:

1. In a plate shaving machine, the combination with a shaving arch adapted to receive a stereotype plate and a shaving knife shaft, of means positioned in front of the entrance to the arch for cleaning the printing surface of said plate pneumatically as the plate enters the arch, comprising an air pipe supply, an air pipe line supported from said supply, jets at the entrance side of the arch and connected with said pipe line, a valve in said pipe line having a stem, and a cam on said shaft for opening the valve and admitting air under pressure into said jets, once during each rotation of the shaft.

2. In a plate shaving machine, the combination with a shaving arch adapted to receive a stereotype plate and a shaving knife shaft, of means positioned in front of the entrance to the arch for cleaning the printing surface of said plate pneumatically as the plate enters the arch, comprising an air pipe supply, an air pipe line supplied from said supply, a manifold with which the air pipe is connected, jets communicating with said manifold and projecting outwardly from the receiving edge of the arch, a valve in said pipe line, and means controlled by the rotation of said shaft for opening the valve and admitting air under pressure into said manifold intermittently.

3. In a plate shaving machine, the combina-

tion with a shaving arch adapted to receive a stereotype plate and a shaving knife shaft, of means positioned in front of the entrance to the arch for cleaning the printing surface of said plate pneumatically as the plate enters the arch, comprising an air supply pipe, an air pipe line supported from said supply pipe, a manifold with which the air pipe is connected, jets constituting exits from said manifold and directing jets of air against the plate, a valve in said pipe line, means controlled by the rotation of said shaft for opening the valve and admitting air under pressure into said manifold during each revolution of the shaft, a plate delivery stand, and means for directing a blast of air on the inside of a plate on said stand from said air pipe for drying the plate.

4. In a stereotype plate finishing machine, the combination with a shaving arch and means for holding a plate therein before being shaved, of means positioned in front of the entrance to the arch for cleaning the printing surface of the plate of metal chips and other foreign matter before it is clamped in the arch and as it enters the arch.

5. In a stereotype plate finishing machine provided with a rotary knife bar shaft and a knife mounted thereon, the combination with a shaving arch, of means for holding the plate in the arch before being shaved, of means positioned in front of the entrance to the shaving arch for cleaning the printing surface of the plate of metal chips and other foreign matter as the plate enters the shaving arch and prior to its being clamped therein, said means comprising an air delivery manifold through which air is directed against the plate at each revolution of the shaft.

6. In a stereotype plate finishing machine, provided with a rotary knife bar shaft and a knife mounted thereon, the combination with a shaving arch and means for holding a plate therein before being shaved, of pneumatic means positioned in front of the entrance to the shaving arch for cleaning the printing surface of the plate as it enters the shaving arch and before being held therein.

7. In a stereotype plate finishing machine, provided with a rotary knife bar shaft and a knife mounted thereon, the combination with a shaving arch, of a spray pipe extending around the entering end of the arch, and means for supplying said pipe with air under pressure at each revolution of the shaft to remove metal chips and other foreign matter from the type surface of the plate as the same enters the arch and before the plate is lifted into contact with the arch.

JAMES F. WILSON.
